UNITED STATES PATENT OFFICE.

JOSEPH B. COMPTON, OF BUCHANAN, KENTUCKY, ASSIGNOR OF ONE-HALF TO F. T. D. WALLACE, JR., OF LOUISA, KENTUCKY.

CUTTING-TOOL.

1,034,345.

Specification of Letters Patent. Patented July 30, 1912.

Application filed January 16, 1912. Serial No. 671,509.

To all whom it may concern:

Be it known that I, JOSEPH B. COMPTON, a citizen of the United States, residing at Buchanan, in the county of Lawrence and State of Kentucky, have invented certain new and useful Improvements in Cutting-Tools, of which the following is a specification.

The tool constituting the subject of my present invention was devised especially with a view to providing improved means for removing the ends of embedded bolts or rods which protrude beyond the surface of concrete work.

It is common practice in molding concrete to have the bolts or tie rods which hold the sides of the form in place extend across the form in such manner as to become embedded in the concrete, and when these forms are removed the ends of such bolts or tie rods are left protruding from the surface of the concrete. Also, it often happens in reinforced concrete work that the ends of reinforcing rods are left protruding from the surface of the concrete. It is important in such cases to remove these protruding bolts or rods by severing them at a point flush with the surface of the concrete. No special tool, prior to my invention, so far as I am aware, has ever been devised for this purpose, the method at present practiced being particularly crude and often resulting in shattering the concrete adjacent the rod or bolt to be cut.

The primary object of this invention, therefore, is to provide a practical form of such tool, though it should be understood that my invention is susceptible to many other specific uses, such as cutting pipes, rods, bolts, or other bodies for various purposes.

In order to more fully describe my said invention reference will be had to the accompanying drawing wherein:

Figure 1, represents in side elevation a form of my improved tool, showing a rod in position, in the tool, to be cut; Fig. 2, a sectional elevation on the line 2^a—2^a, Fig. 1, looking to the left; Fig. 3, top plan view of said tool, and Fig. 4, a detail perspective view of one of the rotary cutters.

My invention in the form herein shown comprises, among other parts, a pair of jaws 1 and 2, the former of which is substantially

hook shaped in side elevation. These two 55 jaws are pivoted together by a pin 3 which extends transversely through the jaw 1 near one end thereof and through a flat sided tongue 4 on the jaw 2, extending into a slot 5 in the end of the jaw 1 referred to. There 60 is quite an extended bearing surface between the side walls of the slot 5 and the tongue 4 so as to reduce the tendency of the jaws to become displaced in a direction transversely to the direction of their pivoted movement 65 or movement to open and close, the reason for which will later more fully appear. The pin 3 is held against lateral movement by a head 6, at one end and a washer 7 at its other end, the said washer being held in 70 place by a taper pin 8.

The cutting mechanism of this tool comprises three circular rotary cutters 9, 10 and 11, preferably truncated cone-shaped, and each having a preferably integral spindle 12 75 extending from the side or face thereof opposite its outer face or base of the cone. Between the spindle 12 and the slanting side of the cutter is a shoulder 13. The spindles of two of these cutters (9 and 10) are journaled in the jaw 1 for rotation, while the spindle of the cutter 11 is similarly journaled in the jaw 2, the spindles in each case extending through the jaws. These cutters are so mounted that their outer flat faces 80 and their cutting edges all lie in a common plane off-set to one side of the jaws of the tool so that the cutting edges of the cutters may be brought up flush against a flat surface and thereby cut a protruding rod or 85 the like at a point flush with said surface. The cutting edges of these cutters are prevented from displacement transversely of the jaws, by the shoulders 13 of the cutters and washers 14 engaging the sides of the 90 jaws, the said washers being held on by taper pins 15, or any other desired means.

In order to further prevent lateral displacement of the cutting edges of the cutters, the jaw 1 is provided with a groove 16, in which is adapted to fit snugly but loose enough to permit of longitudinal movement, a tongue 17 on the jaw 2. The cutters overhang the edges of the jaws 1 and 2 so as to engage a rod, bolt, pipe or other body inserted between them as shown in Fig. 1, where 18 indicates a rod in position to be cut. The jaws 1 and 2 are provided with suitable

handles 19 and 20 and in cases where the cutters are located on one side of the jaws as shown, the handles are off-set to one side of the jaws as shown in order to permit of operating the tool against an extended flat surface.

It will be readily seen that with a tool of this kind projecting ends of bolts, rods and the like may be severed flush with a flat surface such, for example, as concrete, without in the least shattering or damaging the surface adjacent the protruding object.

While I have herein shown and described one specific embodiment of my invention, it should be understood that the same is susceptible of structural modifications which may be made without departing from the true spirit of the invention.

What I claim is:

20 1. A cutting tool of the class described, comprising a pair of jaws pivoted together, rotatable cutters mounted on said jaws and having cutting edges lying in a common plane exterior to said jaws, all other portions of said cutters lying to one side of said plane adjacent said jaws, whereby the cutting edges of all said cutters may be brought flush against a flat surface, certain of said cutters being movable to and away from others by the movement of said jaws on their pivot connection.

25 2. A cutting tool of the class described, comprising a pair of jaws pivoted together, and provided with handles off-set to one side thereof, rotary cutters mounted on said jaws and having cutting edges lying in a common plane exterior to and on one side of said jaws, all other portions of said cutters lying on the side of said plane adjacent said jaws, whereby the cutting edges of all said cutters may be brought flush against a flat surface, certain of said cutters being movable to and away from others by the movement of said jaws on their pivot connection.

30 3. A cutting tool of the class described, comprising a pair of jaws pivoted together, one of said jaws having a longitudinal groove, and the other having a tongue adapted to engage and move in said groove to hold the said jaws against relative displacement in a direction at right angles to their movement on said pivot, and cutters mounted on said jaws, certain of said cutters being movable to and away from others by

the movement of said jaws on their pivot connection.

4. A cutting tool of the class described, comprising a pair of jaws pivoted together, one of said jaws having a longitudinal groove, and the other having a tongue adapted to engage and move in said groove to hold the said jaws against relative displacement in a direction at right angles to their movement on said pivot, and rotary cutters mounted on said jaws and having cutting edges lying in a common plane exterior to and on one side of said jaws, certain of said cutters being movable to and away from others by the movement of said jaws on their pivot connection.

5. A cutting tool of the class described, comprising a pair of jaws pivoted together, and circular rotatable cutters having flat outer faces lying in a common plane exterior to said jaws and having cutting edges terminating in said flat outer faces, said cutters provided each with an integral spindle extending from the side thereof opposite its flat outer face and journaled for rotation in said jaws, certain of said cutters being movable to and away from others by the movement of said jaws on their pivot connection.

6. A cutting tool of the class described, comprising a pair of jaws pivoted together and having handles off-set to one side thereof, and circular rotatable cutters having flat outer faces lying in a common plane exterior to and on one side of said jaws, and having cutting edges terminating in said flat outer faces, said cutters provided each with an integral spindle extending from the side thereof opposite its flat outer face and journaled for rotation in said jaws, certain of said cutters being movable to and away from others by the movement of said jaws on their pivot connection, means to hold said cutters against displacement transversely of said jaws, and means to hold said jaws against relative displacement in a direction at right angles to their pivotal movement.

In testimony whereof I affix my signature in presence of two witnesses:

JOSEPH B. COMPTON.
